United States Patent Office

Des. 229,380

Patented Nov. 27, 1973

229,380

BED

Roland A. Benoit, Danielson, and Richard H. Duprey,
Dayville, Conn., assignors to Interroyal Corporation,
New York, N.Y.

Filed Aug. 23, 1972, Ser. No. 283,047

Term of patent 14 years

Int. Cl. D6—01

U.S. Cl. D6—79

FIG.2

FIG.4

FIG. 1 is a perspective view of a bed showing my new design with the back and knee sections in a raised position;

FIG. 2 is a front elevational view with all sections in a flattened position;

FIG. 3 is a top plan view thereof; and

FIG. 4 is a right side elevational view.

We claim:

The ornamental design for a bed, as shown.
